UNITED STATES PATENT OFFICE.

ERNESTO PERUGGI, OF NEW YORK, N. Y.

DESIGN FOR A DOLL.

55,882.

Specification for Design.

Patented July 20, 1920.

Application filed October 20, 1919. Serial No. 332,125. Term of patent 3½ years.

To all whom it may concern:

Be it known that I, ERNESTO PERUGGI, a subject of the King of Italy, residing at New York city, borough of Manhattan, in the county and State of New York, have invented a new, original, and ornamental Design for Dolls, of which the following is a specification, reference being had to the accompanying drawings, forming part thereof.

In the drawings—

Fig. 2 is a side view thereof.

The figure is usually constructed of plaster or other suitable material.

I claim:

The ornamental design for a doll, as shown.

ERNESTO PERUGGI.
